ATTORNEY.

UNITED STATES PATENT OFFICE.

EUSEBE P. COUTURE, OF GUALALA, CALIFORNIA.

ROTARY ENGINE.

SPECIFICATION forming part of Letters Patent No. 657,590, dated September 11, 1900.

Application filed April 30, 1900. Serial No. 15,003. (No model.)

To all whom it may concern:

Be it known that I, EUSEBE P. COUTURE, a citizen of the United States, residing at Gualala, in the county of Mendocino and State of California, have invented certain new and useful Improvements in Rotary Engines, of which the following is a specification.

My invention relates to an improved rotary engine, the object of my invention being to provide an engine of this character which shall be very simple and cheap in construction, which shall permit of the impulsive force of the steam being used in a very effective and economical manner, in which there shall be only a single movable part, there being no valves, and one which can be reversed at pleasure. My invention therefore resides in the novel construction, combination, and arrangement of parts hereinafter fully specified, and particularly pointed out in the claims.

In the accompanying drawings, Figure 1 is a side elevation of my improved rotary engine, certain parts being broken away to show the internal construction thereof. Fig. 2 is a perspective view of the rotary cylinder removed. Fig. 3 is a similar view of one of the side plates of the casing removed, and Fig. 4 is an end view of the engine broken away to show a section on the line A A of Fig. 1.

Referring to the drawings, 1 represents a suitable bed-plate, upon which are supported the side plates 2 of the engine, each side plate having lugs 3, recessed or grooved, as at 4, to fit tongues 5, formed on the ends of the said bed-plate, the central portion of said bed-plate being concaved circularly, as shown at 6, to receive said side plates. Said side plates are bolted to each other by bolts 7, and between 35 said side plates is mounted the rotary cylinder 8, having a shaft 9, rotating in bearings 10, formed in standards 11, erected upon the bed-plate. Said shaft 9 is preferably formed with tapering or conical ends for greater 40 strength and lightness.

The steam passes by the steam-pipes 12, one on each side of the engine, into a circular conduit 13, formed by a groove cut in the side plate, covered by a plate 14, from which conduit 13 lead conduits 15, formed in the side plate and discharging into a cavity 16, formed in the inner surface of the side plate. Each

cavity 16 has an oblong surface 17 in a plane passing approximately through the axis of the engine and an oblong surface 18 at a considerable angle to the surface 17. In the surface of the rotating cylinder engaging the end plate there are cavities 19 similar to the cavities 16—that is, they have short oblong surfaces 20 in planes approximately passing through the axis of the engine and surfaces 21 sloping at a considerable angle with the surfaces 20. The cavities 16 and 19 will, at a certain point of the revolution of the cylinder 8, form a parallelepiped, as shown in Fig. 4. The conduit 15 emerges in the short oblong surface 17 of the cavity 16, and the steam issues therefrom in such a direction as to impinge upon the short surface 20 of the cavity 19, and thus the cylinder is rotated. As the cylinder rotates it is brought to a point where the cavity 19 passes the cavity 16, and the steam in the latter cavity is cut off or shut in. At the same time steam escapes from the cavity 19 through a conduit 24, which at this stage of the revolution of the cylinder registers with a conduit 25, leading to a circular groove 26, formed on the outside of the side plate. Said groove 26 is covered by an annular plate 27, and thus there is formed an exhaust-channel connected with all the conduits 25 and leading to the exhaust-pipe 28, provided with a suitable cock 29 for controlling the exhaust.

As shown in Fig. 4, the cavities on one side of the engine are arranged around the circle, of which they form a series alternately with the cavities on the other side, so that the engine will receive an impetus from the steam at whatever point it is started, either on one side or on the other.

For the purpose of reversing the engine a second or inner series of cavities 36 39 are formed in the side plates and rotary cylinder, respectively, similar to the cavities 16 19, but having their short square faces turned in the opposite direction. The steam-chambers formed by these cavities are supplied by steam-pipes 32 33. Suitable cocks 40 41 are provided in the steam-pipes 12 32, so that steam may be admitted to rotate the engine in the forward or reverse direction, as may be desired.

In order to prevent escape of the live steam,

brass packing-rings 43 are provided in grooves 44 45 in the side plates and revolving cylinder, respectively.

I claim—

- 5 1. In a rotary engine, the combination of fixed side plates, each having a circular series of cavities in its inner surface, each cavity having a surface in a plane approximately passing through the axis of the engine, a rotating cylinder between the two side plates having a circular series of cavities on each of its faces, said cavities being adapted to register with the cavities in the side plates to form steam-chambers, circular grooves in the outer 10 faces of the side plates, plates covering said grooves to form steam and exhaust conduits, connections through the side plates from said steam-conduits to the several cavities in the inner faces of the side plates, and connections 15 from said exhaust-conduits to the inner faces of the side plates, said connections being arranged to register with exhaust-passages from the cavities in the rotary cylinder, steam-pipes leading to the circular steam-conduits 20 and an exhaust-pipe leading from the circular exhaust-conduit, substantially as described.
- 25 2. In a rotary engine, the combination of fixed side plates, each having an inner and an outer circular series of cavities in its inner surface, each cavity having a surface in a plane approximately passing through the axis 30

of the engine, but said surfaces of the two series having opposite aspects relatively to their respective cavities, a rotary cylinder between the two side plates having inner and outer 35 circular series of cavities on each of its faces, said cavities being adapted to register with the cavities in the side plates to form steam-chambers, inner and outer circular grooves in the outer faces of the side plates, and plates 40 covering said grooves to form steam-conduits, connections through the side plates from said steam-conduits to the several cavities in the inner faces of the side plates, inner and outer circular grooves in the outer faces of the side 45 plates, and plates covering said grooves to form exhaust-conduits, and connections from said grooves to the inner faces of the side plates, said connections being arranged to register with exhaust-passages from the cavities 50 in the rotary cylinder, independent steam-pipes leading to the circular steam-conduits, and a connection between the circular exhaust-conduits, substantially as described.

In witness whereof I have hereunto set my 55 hand in the presence of two subscribing witnesses.

E. P. COUTURE.
